DESIGN FOR A PIPE

Robert V. Barberian, Seattle, Wash.

Application June 20, 1946, Serial No. 130,896

Term of patent 14 years

(Cl. D85—8)

To all whom it may concern:

Be it known that I, Robert V. Barberian, a citizen of the United States, residing at Seattle, Washington, have invented a new, original, and ornamental Design for a Pipe, of which the following is a specification, reference being had to the accompanying drawing, forming part thereof.

Figure 1 is a perspective view of a pipe, showing my new design.

Figure 2 is an elevational view of the bowl end of the pipe shown in Figure 1, and

Figure 3 is an elevational view of the stem end thereof.

I claim:

The ornamental design for a pipe, as shown.
ROBERT V. BARBERIAN.
